[57] CLAIM

The ornamental design for a water dam for a flush tank,
as shown and described.

DESCRIPTION

FIG. 1 is a front perspective view of a water dam for a
flush tank showing my new design;

FIG. 2 is a cross sectional view taken on line 2—2 of
FIG. 1;

FIG. 3 is a rear perspective view thereof; and

FIG. 4 is a top plan view thereof with a portion omitted
for convenience of illustration.
